UNITED STATES PATENT OFFICE.

WILLIAM E. WOODARD, OF FOREST HILLS, NEW YORK.

LOCOMOTIVE.

Application filed October 20, 1922. Serial No. 595,757.

This invention relates to improvements in locomotives and particularly to the means whereby steam is taken from the boiler and supplied to the engines.

One of the primary objects of my invention is to improve the efficiency and operation of existing locomotives; and also their auxiliaries.

Another object of my invention is to make super-heated steam available for the locomotive auxiliaries at all times, irrespective of whether the throttle is open or closed.

A further object of the invention is to provide an emergency control valve to be used, for example, in case of inspection or repair with steam on the boiler or accident to main throttle valve which sometimes renders such valves inoperative, resulting in serious damage as the engine is out of the control of the engineman.

Among the more specific objects of my invention is the provision of an improved arrangement of throttle box; and throttle box connection to the superheater header.

The foregoing, together with such other objects as may hereinafter appear or are incident to my invention, I obtain by means of a construction which I have illustrated in preferred form in the accompanying drawings, wherein:

Fig. 1 is a broken away longitudinal section through a locomotive fire box boiler and smoke box, illustrating the application of my improvements; Fig. 2 is a fragmentary side elevation of Fig. 1; Fig. 3 is an enlarged section with parts in elevation taken on the line 3-3 of Fig. 1; and Fig. 4 is a similar enlarged section taken on the line 4-4 of Fig. 1.

Referring now to Fig. 1, the reference letter A indicates the back head of the locomotive; B is the firebox; C is the locomotive boiler shell; D is the smoke box; and E is the front flue sheet. The reference letter F denotes the standard type of superheater header provided with two outlets 7 and 8 to which, in ordinary practice, the steam pipes leading to the valve chests are directly connected.

In accordance with my invention I interpose a throttle unit G between the superheater header and the steam pipes, such unit consisting of the throttle box 9 and a double or U-shaped connection 10. The throttle box lies within the smoke box so as to be subjected to the hot gases of combus-

tion and is supported from the shell thereof, in advance of the stack 11, the branches of the double connection passing around the stack on either side and being respectively coupled to the outlets 7 and 8 of the superheater header. The throttle box is also provided with two outlets 12 and 13 to which the steam pipes 14 and 15 are respectively connected. The throttle box, double connection and outlets 12 and 13 are preferably cast integral. The throttle valve 16 is accessible from the exterior of the smoke box by removing the cover and the throttle box closure plate 17; and the valve is operated by the operating mechanism 18 extending to the cab.

The dry pipe 19 may, in general, be of standard construction, but I provide an intake end 20 therefor which is of elbow shape. The intake end of the dry pipe is provided with a valve seat 21 for an emergency control valve 22, the valve rod 23 of which extends through the back head A and has, at the rear end thereof, threaded connection 80 with the bonnet 24. Leakage is prevented by means of the packing 25. The emergency valve is normally maintained in open position but may be closed, for example, if there is any work to be done on the superheater units with steam on the locomotive or if the throttle valve should get out of order, and the like; or used as a control valve for operating the locomotive if the throttle should get out of order on the road. 90

The upper end of the intake extends within the steam dome 26 and carries certain parts which cooperate with the dome to constitute a steam separator. The separator parts comprise the bell-shaped flanged member 27, the hood 28, and the inclined baffle member 30. The steam is deflected and caused to take the tortuous path indicated by the arrow and the water is separated out and such as collects in the bell is returned to 100 a suitable point in the boiler, as by the drain pipe 32.

It will be seen from the foregoing that existing locomotives may be adapted to receive my improvement by removing the throttle from the dome and substituting a new dry pipe or a new dry pipe end and the separator elements; and removing the steam pipes and interposing the throttle unit described. Thus space is provided for the steam separator and at the same time the emergency valve can be readily applied. 110

The provision of the separator ensures dryer steam in the dry pipe and a higher degree of superheat and therefore more efficient operation, and the location of the throttle box in the smoke box also furthers this object.

By taking off the steam supply for locomotive auxiliaries at a point in the throttle box unit, for example, at 31 (see Fig. 4), superheated steam is always available for such auxiliaries irrespective of whether the throttle is open or closed and the operation of the auxiliaries is improved and made more efficient.

Other advantages will occur to those skilled in the art.

What I claim is:

1. The combination in a locomotive having a smoke box and an inside steam supply line including a superheater, of a main normal control throttle in the smoke box on the chest side of the superheater through which all steam to the chests must pass, an outside operating connection therefor leading to the cab, an emergency valve in the steam line on the dome side of the superheater, and an operating connection for such valve extending within the boiler to the cab.
2. In a locomotive having a smoke box, a dry pipe, a superheater, a steam line from the superheater to the chests, a throttle mounted in the smoke box in said steam line through which all steam to the chests must

pass, a take off for an auxiliary between the superheater and the throttle, and a shut-off valve in the dry pipe on the dome side of the superheater.

3. In a locomotive having a smoke box, a dry pipe, a superheater, a steam line from the superheater to the chests, a throttle mounted in the smoke box in said steam line through which all steam to the chests must pass, a take off for an auxiliary between the superheater and the throttle, and a shut-off valve in the dry pipe on the dome side of the superheater, said take off being located in the smoke-box.

4. The combination in a locomotive having a smoke box, steam chests, steam dome, and an inside steam supply line, of a superheater in said line having a header, a main normal control throttle in the smoke box through which all steam to the chests must pass, an outside operating connection therefor leading to the cab, a separate pipe connection from each end of the superheater header to said throttle, connections from the throttle to the chests, an emergency valve in the steam line located within the boiler between the superheater and the dome, and an operating connection for such valve extending within the boiler to the cab.

In testimony whereof, I have hereunto signed my name.

WILLIAM E. WOODARD.
